UNITED STATES PATENT OFFICE.

JOSE J. GUERRA, OF CIUDAD JUAREZ, MEXICO.

CHECK-PROTECTOR.

1,238,665.

Specification of Letters Patent. Patented Aug. 28, 1917.

Application filed March 3, 1916. Serial No. 81,991.

To all whom it may concern:

Be it known that I, JOSE J. GUERRA, a citizen of the Republic of Mexico, residing at Ciudad Juarez, in the Province of Chihuahua, Mexico, have invented certain new and useful Improvements in Check-Protectors; and I do hereby declare the following to be a full, clear, and exact description of the invention, such as will enable others skilled in the art to which it appertains to make and use the same.

The invention relates to improvements in check protectors.

The object of the present invention is to improve the construction of check protectors and to provide a simple, practical and comparatively inexpensive construction adapted for use in connection with a fountain pen and capable of being readily applied to the cap thereof and of also forming a clip for securing the fountain pen in the pocket as well as partially perforating and weakening the portion of the check on which the amount is written thereby effectually preventing a check from being raised.

A further object of the invention is to provide a check protector of this character, which will be sufficiently small to be easily carried in the outer portion of the cap of a fountain pen whereby the device will not interfere with the arrangement of the cap on a fountain pen and will enable a cap equipped with the check protector to be readily substituted for an ordinary cap where it is designed to equip a fountain pen with the improved device for protecting checks.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawing—

50 Figure 1 is a side elevation of a fountain pen provided with a check protector constructed in accordance with this invention.

Fig. 2 is a similar view of the outer portion of the fountain pen, the latter being 55 in a different position to show the lever in front elevation,

Fig. 3 is an enlarged longitudinal sectional view of a fountain pen cap equipped with a check protector, the body portion of the fountain pen being illustrated in dotted lines and broken away,

Fig. 4 is an end elevation of the fountain pen,

Fig. 5 is a transverse sectional view taken substantially on the line 5—5 of Fig. 3.

Like numerals of reference designate corresponding parts in the several figures of the drawing.

In the accompanying drawing in which is illustrated the preferred embodiment of the invention, 1 designates a fountain pen provided with a removable cap 2 having a central slot or bifurcation 3 in its outer end and provided also with a transverse partition 4 dividing the cap into inner and outer spaces or compartments 5 and 6, the inner space or compartment being adapted to receive the outer portion of the barrel or tip of the fountain pen as clearly illustrated in dotted lines in Fig. 3 of the drawing. The cap is provided at its outer end with rounded portions 7 forming a flaring mouth or entrance to the slot or bifurcation 3 which is adapted to receive a check in a folded condition to permit the portion of the check bearing the amount to be operated on by a pair of rollers or cylinders 8 and 9 having a toothed peripheral outer face forming projecting spurs or partially perforating the check and weakening the same and also roughening the protected portions to render it impossible to raise a check.

The cylinder or roller 8 is mounted on a shaft or spindle 10 which is journaled in suitable bearings of ears or lugs 11 preferably formed integral with the cap and located at one side thereof opposite a side opening 12. The other cylinder or roller 9 is mounted between spaced bearing lugs or ears 13 which are carried by the outer arm 14 of a longitudinally disposed lever 15 located exteriorly of the cap and fulcrumed thereon at a point intermediate of its ends. The longitudinally disposed lever is designed to be constructed of suitable spring metal or other resilient material and it is provided at or near its center with a curved inwardly extending bend 16 presenting a rounded convex face to the side of the cap and secured to the same by a rivet 17 which pierces the cap and the lever. The bend spaces the inner and outer arms of the lever

or member 15 from the sides of the cap and the bearing ears or lugs 13 which extend through the side openings 12 are provided with perforations disposed in longitudinal alignment and receiving the shaft or spindle 18 on which the roller 9 is mounted. The inner arm 19 of the resilient lever or member is provided with a head 20 preferably in the form of a ball and constituting means for engaging the exterior of a pocket to clamp the material between it and the fountain pen whereby the latter is retained in the pocket and is prevented from falling accidentally therefrom. The resiliency of the outer arm 14 of the lever or member 15 normally maintains the roller or cylinder 9 in spaced relation with the roller or cylinder 8 and when it is desired to protect a check, the latter is folded so that the space bearing the amount of the check will occupy a position adjacent to the line of the fold. The folded portion of the check is then placed between the rollers by introducing it into the slot or bifurcation 3 and the check is then drawn through the rollers while compressing the folded portion of the check by pressing against the arm 14 and the cap. The check will readily roll through the toothed rollers or cylinders without tearing the paper.

What is claimed is:—

1. A check protector including a supporting member provided at its outer end with a slot or bifurcation and having spaced bearings at one side of the slot or bifurcation and provided at the opposite side thereof with an opening, a pair of check protecting rollers or cylinders arranged within the

said supporting member, one of the rollers or cylinders being mounted between the said bearings, a resilient lever extending longitudinally of the supporting member and arranged exteriorly thereof and secured intermediate of its ends to the same, said lever having an inner pocket clamping portion or arm coacting with the inner portion of said supporting member to engage a pocket to retain the check protector therein, the outer portion of the lever having spaced bearings extending through the said opening and carrying the other roller or cylinder, said lever being adapted to be operated to cause the rollers or cylinders to engage a check.

2. A check protector including a supporting member, a roller or cylinder mounted on the supporting member, a pocket clamping lever extending longitudinally of said supporting member exteriorly thereof and connected at a point intermediate of its ends to the same and having an inner clamping arm arranged to coact with the inner end of the said member to engage a pocket to retain the check protector therein, and a roller or cylinder carried by the outer arm of the clamping lever and coacting with the first mentioned roller or cylinder to engage a check and adapted to be operated by the said lever, the latter being arranged to hold the rollers or cylinders normally separated.

In testimony whereof I affix my signature in presence of two witnesses.

JOSE J. GUERRA.
